CLAIM

The ornamental design for an insulating beverage case, as shown and described.

DESCRIPTION

FIG. 1 is a front view of the insulating beverage case, with the back view being identical, shown in a collapsed configuration;

FIG. 2 is a front and bottom perspective view thereof;

FIG. 3 is a front and right perspective view thereof;

FIG. 4 is a front and top perspective view thereof;

FIG. 5 is a top perspective view thereof;

FIG. 6 is a right perspective view thereof, with the left perspective view being identical;

FIG. 7 is a bottom perspective view thereof;

FIG. 8 is a front view of the insulating beverage case, with the back view being identical, shown in an open configuration;

FIG. 9 is a front and bottom perspective view thereof;

FIG. 10 is a front, right, and bottom perspective view thereof;

FIG. 11 is a front and right perspective view thereof;

FIG. 12 is a front and top perspective view thereof;

FIG. 13 is a front, right, and top perspective view thereof;

FIG. 14 is a right and top perspective view thereof;

FIG. 15 is a right perspective view thereof, with the left perspective view being identical; and,

FIG. 16 is a right and bottom perspective view thereof.

The broken lines illustrate portions of the insulating beverage case that form no part of the claimed design. The overlapping curly lines shown in FIGS. 2–7 and 10–16 depict a contrast in appearance.

1 Claim, 8 Drawing Sheets
